Dana Hubbard, Wheeling, Virginia
Letters Patent

The schedule referred to in these Letters Patent and making part of the same containing a description in the words of the said Dana Hubbard himself of his improvement in the machine for cutting Laths for Pastures, etc.

To all whom these presents shall come,
Be it known that P. Dana Hubbard of the Town of Wheeling in the County of Ohio and State of Virginia has invented a new and useful improvement in the machine for cutting Laths for Pastures, etc., and that the following is a full and exact description of the construction & operation of the said machine as invented by me. The machine consists of a strong frame or bench made of timber 6 inches square and should be about 8 feet long, from 2 to 3 feet wide & of a convenient height say from 2 to 3 feet, with a pair of braces and stays to stiffen it. The inner edges of the top rails of this frame, are to be grooved so as to receive a plank about 3 inches thick of the width of the frame between the grooves, and about a foot shorter than the grooves, i.e. 7 feet so as to admit of its sliding endwise the distance of 8 or 10 inches. This plank is intended to bear the cutting knife as hereafter described, in its middle end, at an angle of about 20 degrees with its edge, an oblique mortise or slot is to be cut through the plank of from 2 to 3 inches broad, and about 1 foot 8 inches long, or the length of the knife. To one side of this groove, fastened by screws to the upper surface of the plank, is the knife, the blade of which lays over the mortise. The knife may be made wholly or partly of steel, properly planed about 1/8 inch thick, and 1 foot 8 inches long, its right edge the whole length of the groove, and its edge standing obliquely upward at a height above the surface of the plank equal to the thickness of the intended lath, equivalent from the ends of the bench, and so as to contain the length of the lath between them. Two strong timbers are laid across the room, and fastened with screws, etc. on the top rails intended for the purpose of holding down the sliding plank when moved and to form braces for the ends of another piece.

strong piece of timber placed obliquely and secured by bolts to the said cross pieces, so that the face next to the knife coincides with the edge of the knife, at the end of its cutting motion. This oblique cross piece is intended to answer the purpose of a cutting block and receives the pressure and supports the material from which the laths are to be cut during the operation - for the better accomplishing this purpose two perpendicular arms are mortised into the upper side and appear to steady the material when broad, the ends of the material being secured in the notches or grooves. One of these may be prolonged by an upright arm or guide corresponding to the width of the intended lath, made in the aforementioned cross pieces or bearings. This oblique piece is also secured with a bar of iron or steel of the thickness of the lath to be made, being secured to its lower side by screws and above the upper surface of which the edge of the knife passes at the end of the cutting motion, and that the latter may leave a short distance past the edge of the former, the lower corner of the oblique timber is to be champed before attacking the bar thereto, by this means the knife passes between them and will make a cleaner cut. To one end of the sliding planks is attached a pinion to be connected with the cranks of the moving power of the machinery which may be Horse, Plum or water &c. In the machine which I have in use I have found it convenient to produce that lateral of the bench which is next to the ship about 8 feet, and constructed on the part so produced, and on the opposite side a strong frame like that of the bench, across this frame near its centre of fix the shaft which has the driving band pulley, and a low, or shifting pulley, in the middle and a balance wheel on the end next the bench to the 14 inch stand, of which latter the platen is attached. I also have the upright posts of the frame farther from the cutting bench, and have a band lightning roller placed in a small gate or frame, that works in grooves in the inner side of said posts, the gate being raised or lowered by a lever the end of which rises to the front or leading point of the machine and which has its fulcrum on a cross piece supported upon uprights raised from the frame near the shaft, for further convenience the last mentioned cross piece has a long groove or slot, through which the end of another lever passes that has its fulcrum on the top of the gate, and the arm beyond the

589

Gate being fastened so as to stick the hand of the driving handle, the operator by means of it can throw the machine in or out of gear — Operation. The material is first prepared by sawing it into blanks of proper thickness and length, to make the intended laths, it is then to be placed edgewise upon the sliding plank being supported against the front of the oblique line between cutting blocks, the ends resting in the grooves of the cross pieces into which they pass freely — The machine is then set in motion, whereby the compound motion occasioned by the sliding of the plank, and the oblique position of the knife, the lath is partly cut and partly raised from the bottom edge of the bottom edge of the material, between the knife and shoe and drops through the groove, whereupon the knife draws back, the material falls into its place, and the operation is repeated till the material is exhausted. The machine fading itself after the pieces are made in.

Although I describe the machine as operating horizontally, and have selected an 80 degrees as the best obliquity for the knife, I assume the right of varying this and of making it operate vertically, inclined; or otherwise by making the necessary alteration, and effecting however the principles herein claimed — Now what I claim as new and as my invention is the oblique position of the knife, which together with the sliding of the plank to which it is attached, and the stationary cutting block, produces the compound motion, that partly cuts, and partly raises the lath from the prepared material, with little expense of power — Washington July 16, 1834.
